UNITED STATES PATENT OFFICE.

RAFFAELE MORELLI AND JOSEPH SOLIMEO, OF BROOKLYN, NEW YORK, ASSIGNEES OF ONE-FIFTH TO ADDIECO MIRRA, ONE-FIFTH TO EMILIO MIRRA, AND ONE-FIFTH TO DONATO INZALATA, ALL OF BROOKLYN, NEW YORK.

CLEANING APPARATUS.

1,327,110.

Specification of Letters Patent.

Patented Jan. 6, 1920.

Application filed January 5, 1918. Serial No. 210,531.

To all whom it may concern:

Be it known that we, RAFFAELE MORELLI and JOSEPH SOLIMEO, subjects of the King of Italy, residing at the borough of Brooklyn, 5 city of New York, in the county of Kings and State of New York, have invented certain new and useful Improvements in Cleaning Apparatus, of which the following is a specification, reference being had therein to 10 the accompanying drawings, forming part thereof.

Our invention relates to clothes cleaning apparatus and more particularly to automatically operated brushes used for this 15 purpose.

Heretofore in the cleaning or pressing of clothes, the cleaner or presser has used a cloth moistened with a cleaning fluid such as naphtha, benzin or the like to rub the 20 dirt or grease spots from the clothes, and he has used the ordinary clothes brush or whiskbroom to brush the dirt and dust off. An object of our invention is to avoid these 25 manual operations of cleaning and brushing and to perform them automatically and in a single operation, if necessary.

Our invention comprises an automatically 30 rotatable brush adapted to be moved into and out of operable position on the pressing table, the brush being hollow and containing means for holding a cleaning fluid that can be discharged into the brush at will. The invention also comprises means for moving the brush into and out of operation when 35 it is positioned on the table.

The entire cleaning apparatus may be 40 moved from one table to another when it is so desired, or it may be moved so that the brush will operate in various positions on the table.

Other more particular objects of our invention will appear from the following description.

We shall now describe the embodiments of 45 our invention illustrated in the accompanying drawings and shall thereafter point out our invention in a claim.

Figure 1 is a side elevation of our cleaning apparatus showing the brush on the 50 pressing table, the dotted lines indicating the brush in lowered position.

Fig. 2 is a plan view.

Fig. 3 is an enlarged end elevation of the rotatable brush.

Fig. 4 is a longitudinal sectional view 55 of brush taken on the line $x-x$ of Fig. 3.

Fig. 5 is a cross sectional view of the brush taken on the line $y-y$ of Fig. 4.

In the embodiment of our invention illustrated in the drawings, the cleaning apparatus consists of a table 1 having legs 2 and supporting brackets 3. The table is provided with a flap 4 and hinges 5, the flap being adapted to be raised above the table 65 for the reasons hereinafter set forth.

A rotatable brush 6 is mounted on a hollow arm 9. The arm 9 is pivoted on the shaft 10 of a motor 8 which is secured to a platform 11. This platform is provided with rollers or bearings 12 so as to allow 70 the platform to move. The brush 6 is provided at each end with a table-rest 7. The brush 6 is rotated by means of a belt 22 located inside of the arm 9 and fixed about the shaft of the motor 8 and a wheel 21 75 secured to the shaft 20 of the brush. The hollow arm 9 acts also as a guard for the belt. A table rest 7 is provided with an angular slot 27. The shaft 20 of the brush 6 rotates in bearings 26 located at the top 80 of the angular slot 27 and held normally in position there by means of a spiral spring 28 bearing at one end against the bottom of the slot 27 and at other end against the bearing 26. By this means the brush is 85 normally and when not operating kept above the table.

The rotatable brush 6 is provided with bristles 15 secured to outer cylindrical shell 16. This shell has a side frame 16^a and is 90 secured to shaft 20 by means of a screw 16^b. A cylindrical tube or tank 17 is located in the shell 16 and is adapted to rotate therein. This tube or tank 17 is used as a reservoir for cleaning fluid. Rows of perforations 18 are provided in the inner tube 17 and are in alinement with rows of perforations 19 provided in the outer shell 16. The shaft 20 of the brush 6 is hollow. A pipe 23 is adapted to rotate in such shaft and 100 is fixed at one end to the tank 17. A removable cap 24 is provided at the other end and a hand wheel 25 is secured to the pipe. When it is desired to supply cleaning fluid to the bristles of the brush the 105 handwheel 25 is turned slightly thus rotating the tank 17 until the perforations 18 therein register with the perforations 19 in

the outer shell. When these perforations register an outlet is provided for the cleaning fluid to the bristles 15. When enough cleaning fluid has been passed through the perforations the handwheel is again turned to bring them out of register. Indicating means may be provided for showing whether the perforations are in register or not. When the tank 17 is empty, it can be refilled by removing the cap 24 and pouring the fluid through the pipe 23. When the tank is replenished the cap 24 is replaced. The brush is provided with a shield 13 having a handle 14.

When not in use the brush would normally be in the position shown in dotted lines in Fig. 1, where it rests on the platform 11, where it rests on the platform 11. When the operator desires to use the brush, he raises the flap 4, lifts the brush by the handle 14 swinging it about the shaft 10 of the motor 8 until it is above the table. The flap 4 is then dropped and the brush is lowered until the table-rests 7 are on the table. The bristles of the brush in this position are above the table and the article to be brushed or cleaned is slid under the brush. The current supply for the motor is then turned on by means of a switch (not shown) suitably located, or means may be provided whereby the current is automatically turned on when the brush is pressed down, thus rotating the

brush by means of the belt 22. To bring the rotating brush into operation, the operator presses the shield 13 down against 35 the tension of the springs 28 in the slots 27 in the table-rests 7, and the brush is lowered until it contacts with the article. When such pressure is released the brush immediately rises out of operating position. 40 When the operator has finished his brushing operation he can move the brush to one end of the table or he can lower the brush to the platform 11. It will be seen that by means of our invention the brushing and cleaning 45 operation can be accomplished in a few seconds in a sanitary and thorough fashion.

It is obvious that various modifications may be made in the constructions shown and above particularly described within the 50 principle and scope of our invention.

We claim:

A rotatable brush comprising an outer bristle holding shell, an inner fluid containing tank rotatable within such outer shell, 55 perforations in both the outer shell and the tank, means for bringing such perforations into and out of register, and means to rotate the brush.

In testimony whereof we have affixed 60 our signatures.

RAFFAELE MORELLI.
JOSEPH SOLIMEO.
